UNITED STATES PATENT OFFICE.

THOMAS ARTHUR WOOLEY AND HERBERT FOX, OF HAMILTON, CANADA,
ASSIGNORS OF ONE-HALF TO ADAM ZIMMERMAN, OF SAME PLACE, AND
ARTHUR ERNEST OSLER, OF TORONTO, CANADA.

MACHINE FOR SHOCKING GRAIN.

SPECIFICATION forming part of Letters Patent No. 656,280, dated August 21, 1900.

Application filed December 6, 1899. Serial No. 739,360. (No model.)

To all whom it may concern:

Be it known that we, THOMAS ARTHUR WOOLEY and HERBERT FOX, citizens of Canada, residing at Hamilton, in the county of 5 Wentworth and Province of Ontario, have invented certain new and useful Improvements in Machines for Shocking Grain; and we do hereby declare the following to be a full, clear, and exact description of the invention, such 10 as will enable others skilled in the art to which it appertains to make and use the same.

Our invention relates to improvements in machines for shocking grain, in which a frame with sheaf-receiving carrier is attached to a 15 grain-reaper and binder-machine in such a manner as to allow the sheaves from the said binder to be placed on said carrier in a vertical position—that is, the butt-ends downward by means of certain curved guide-rods 20 secured to the binder; and the objects of our improvements are, first, to provide a machine attached to a binder in such a manner that the said binder shall be capable of proper adjustment to suit the different lengths of grain and 25 also the varying high and low ground without interfering with the relative position of the shocking-machine to the ground drive-wheel of the binder; second, to provide means for placing the sheaves horizontally delivered 30 by the binder to a vertical position on the carrier of the shocker. We attain these objects by the mechanism illustrated in the accompanying drawings, in which—

Figure 1 is a plan of the framework of a 35 shocking-machine attached to a reaper and binder in diagrammatic plan and means for guiding the sheaves lying in a horizontal position on the binder to a vertical position on the carrier of the shocker, the incline sheaf-deck of the binder being merely outlined in order not to hide the mechanism beneath. Fig. 2 is a front elevation of the same, showing a sheaf being guided onto the shocker. Fig. 3 is a side elevation of the framework and the 40 sheaf-carrier of the shocker, and Fig. 4 is a side elevation of the shocking-machine-carrying device as seen connected principally to the axle of a binder-machine.

Similar characters refer to similar parts 45 throughout the several views.

In the drawings, A is the frame of the shocker, preferably constructed of angle-iron and of suitable length to meet all necessary requirements, and B is the metallic frame of a reaper and binder machine. This shocker-frame is attached to the sheaf-discharge side of the binder by means of the transverse supporting bar or tube C, on which the sheaf-receiving end of the frame A is supported and secured thereto. The inner end of this bar C 55 extends upward through the binder-frame and is widened out at the top and concaved, as at 2, to have a proper bearing to fit against the under part of the stationary axle D of the binder ground drive-wheel E and against the 60 shoulder formed by the hub H. This axle fits into brackets or housings F and G of the binder-frame. This concaved part 2 of the bar C fits against the hub H of the wheel E to retain said bar in position. The upper 65 bracket J of the shocker-carrying device is also concaved, as at 3, to fit on the said axle of the wheel E and against its hub H in like manner as the upturned end of the bar C at 2. This bracket J extends a distance on 70 each side of the hub H, and both ends extend vertically upward a distance apart from each other to act as a stationary side brace and 75 steady support for the bar C when the said bar C is braced to the upper parts of the said 80 vertical extensions, as at 4. This support C is braced by means of the double brace-rod K, which is secured to the vertical end of the bracket J, as at 4, and to the bar C at 5, where the double rod K joins together as one. 85

M is an angle-iron brace on the top of the wheel-axle guide F and acts as an outer stay for the bracket J and is a part of the binder-frame, as is also the axle-guide G on the opposite side of the wheel E. These axle-guides 90 F and G, together with the brace M and the frame B, are capable of being raised and lowered and are a part of the mechanism of the binder which we do not claim.

N is the inclined sheaf-deck of the binder, 95 and O is the horizontal knotter-shaft, which is operated in its horizontal bearing P, which forms a part of the lower supporting part R, which is a part of the binder. On this deck N the sheaves are formed and bound and are 100

then discharged by the arms S of the knotter-shaft of the binder and revolve the way the arrow points. The arms S convey the bound sheaves between the guide-rods from the 5 binding mechanism.

In order to guide the bound sheaf from a horizontal position and from the deck N, a suitably-curved guide-rod U is secured to the forward outer part 6 of the breast-plate T, 10 and a suitably-curved upper stay branch V of said guide U is secured to a lug 7 of the binder-knotter-shaft bearing P. The lower and rear sheaf-guiding rod W is also suitably curved toward the rear and upward and is secured 15 at 81 to the binder-deck N and between the middle and rear discharge-arms S of the binder. The guide-rod U, with its branch V, is located between the two forward arms S of the binder.

20 The butt-end of the sheaf is located at the forward end of the binder and is seen in broken line X to show the purpose of the guide-rods in Fig. 2 of the drawings and in the act of being positioned from a horizontal 25 sheaf to a vertical sheaf on the receiving end of the carrier Y of the shocker by the power of the arms S of the binder. The sheaves being changed from a horizontal to a vertical position by the power of the discharge-arms 30 S of the binder, the butt-end of the sheaf is carried on the plate Z, which is secured to the discharging side of the deck N of the binder and located above the receiving end of the shocker. At this changing of position of the 35 sheaves the butt-end of the sheaf is on the plate Z and is guided to vertical position by the under side of the guide-rod U, while the grain end of the sheaf is guided upward to vertical position by the upper side of the 40 guide-rod W and landed on the carrier of the shocker in a vertical position by the power and force of the discharge-arms S, which gives the sheaves sufficient momentum to attain to this vertical position. The outline X' of a 45 sheaf is shown in Fig. 2 of the drawings as discharged and being guided to vertical position by the power of the discharge-arms S and by means of the guide-rods U and W of the binder. The lower part of the sheaf is broken 50 away, so as not to interfere with this view of the shocker. The sheaf-carrier Y is located at the sheaf-receiving end of the shock-machine and is supported obliquely by the frame A by means of side brackets 8 and 9, which 55 are secured to said frame and to the sides 10 of the carrier.

The carrier is higher at the receiving end than the discharging end and is revolved by means of the lower transverse shaft 13 in 60 bearings 9 of the frame. This carrier is preferably inclined, as stated, to facilitate the carrying of the sheaves toward the discharging end of the shocker. The inner end of the transverse shaft 13 is supplied with a gear-wheel or sprocket-wheel 14 to receive continuous power from the binder by means of mechanism. The receiving end of the car-

rier is supplied with belt or sprocket wheels 15 on studs 16 of the sides 10, and the shaft 13 is supplied with belt or sprocket wheels 70 17. The belt or chain 18 runs on these wheels and carries the transverse slats of the sheaf-carrier Y, which are secured to said belts or chains and revolve with the same toward the discharge end of the shocker. To prevent 75 the stub ends of the butts of the sheaves from protruding too far through the spaces formed by the transverse slats of the carrier, a board 19 is provided in proximity to the under side of the carrier and extends as far as possible 80 in the carrier without interfering with the revolutions of the carrier. This board extends transversely from one side 10 to the other side 10 of the carrier Y and is stationary with said sides. 85

20 and 21 show the position of the vertical needle and knotter shafts, respectively, in their stationary columns 22 and 23, and 24 shows the position of the sheaf-dividing board, the sheaf-receiving end of which is 90 pivoted at 25, which is controlled by mechanism at the reception of each sheaf.

The caster-wheels 26 support the discharging end of the shock-machine frame A.

It will be observed that the framework of 95 the shocker and the revolving carrier therein will be positioned to the discharging side of a binder to attain the proper results, as set forth.

The side rails 27 of the shocker are secured 100 to the brackets 8 of the frame A and to the columns 22 and 23, as at 28, as seen in Fig. 3 of the drawings. One of these side rails are shown only in Fig. 3 of the drawings.

It will be noticed that the sheaf-guiding 105 rods U and W will be of sufficient length and of proper curvatures and will project over the shocker sufficiently to accomplish their object of placing the sheaves successively in vertical position on the carrier and at the same time 110 offer no obstruction to the sheaves passing along toward the discharging end of the shocking-machine and forming a shock.

What we claim as our invention, and desire 115 to secure by Letters Patent, is—

1. A shocking-machine attachment to the discharging side of the binder, comprising a transverse bar, or tube, the binder end of said bar turned to vertical position and concaved to fit against the under side of the stationary axle of the binder and between the hub of the ground-wheel and the axle-housings, thereof, a bracket fitting on the top of said axle and against said hub, vertical ends to said bracket a distance apart, a double 125 brace-rod secured to the ends of the bracket and to the lower transverse bar to support the receiving end of a shocking-machine, independently to the adjustment of the binder, as described.

2. A shocking-machine attachment to the discharging side of a binder comprising a transverse support, the binder end of said support extended vertically to fit to the under side of

the stationary axle of the ground-wheel and the end of the hub, a bracket extending across and fitting on the said axle and against the said end of hub and between the binder-frame

5 and the wheel, vertical extensions to the ends of said bracket, a double brace-rod secured to said vertical extensions, and apart, the lower end of said brace-rod secured to the said transverse bar to support the same, the 10 receiving end of a shocking-machine frame secured on the outer part of said transverse bar, as described.

3. In a binder-machine, sheaf-guide rods secured to the discharge side of the binder 15 and above the inclined sheaf-deck thereof, the forward said rod formed with stay branch and outwardly and upwardly and then downwardly curved to guide the butt-end of the discharged sheaf downward, in combination 20 with the rear guide-rod positioned and suitably curved upward and to the rear to guide the head of the sheaf upward and place the same in a vertical position on the carrier of a shocker by the power of the discharging- 25 arms of the binder.

4. A binder and shocker comprising sheaf-guide rods secured to the discharge side of a binder, the forward rod with its stay branch positioned at the discharge side of the forward discharge-arms of the binder, and said rod extending over the attached shocker, said rod being outwardly and upwardly and then downwardly curved to guide the butt-end of the discharged sheaf downward, an incline- 35 plate secured to the discharge side of the binder and forward of said guide-rod and extending to the shocker to receive the butt-end of the sheaf, the rear sheaf-guide rod positioned at the discharge side of the middle 40 and the rear discharge-arms of the binder, and extending over the shocker, said rod be-

ing upwardly and rearwardly curved to guide the head of the sheaf upward in vertical position by the power of the discharge-arms of the binder.

5. In a shocking-machine, a transverse bar or tube for supporting the receiving end of the machine, said bar or tube, engaging the under part of the stationary axle of the drive-wheel of a binder, and at the discharging side 50 of the binder, a bracket having upwardly-extending ends, stay-rods connecting said transverse bar to the upper extended ends of the bracket, said bracket supported on and by the said stationary axle and against the hub 55 of said wheel, a carrier at the receiving end of said machine, and in oblique position inclining downward toward the discharging end thereof, slats on said carrier, supporting-brackets secured to the frame of the shocker 60 and to the sides of said carrier and a shaft supported by the brackets, carrier-sprockets on said shaft, a gear or sprocket wheel secured on said shaft, at the binder end, to connect to binder mechanism and receive continuous power, side studs at the receiving 65 end of the carrier to support the carrier-sprockets, a board between the sides of the carrier and beneath the sheaf-carrying slats thereof and an incline-plate secured to the 70 deck of the binder and projecting to the receiving end of the shocker to carry the butt-ends of the sheaves when being changed from a horizontal to vertical position, as described.

In testimony whereof we affix our signatures in presence of two witnesses.
